UNITED STATES PATENT OFFICE.

EDGAR M. BENHAM AND WILLIAM T. BENHAM, OF NORWOOD, OHIO, ASSIGNEES TO THE MOSLER LOCK COMPANY, OF COVINGTON, KENTUCKY, A CORPORATION OF OHIO.

PROTECTION DEVICE FOR TUMBLER LOCKS.

Application filed January 10, 1927. Serial No. 160,036.

This invention relates to locks and more particularly relates to a protection device for tumbler locks designed to frustrate attempts to open the lock by tampering with the mechanism in an unauthorized manner.

Tumbler locks especially the combination locks for safes, and the like, which have a spindle for setting the combination tumblers, are frequently constructed in such a way that 10 the lock can be opened readily after a person has succeeded in removing the knob from the spindle and then driving the spindle inwardly into the safe. This is due to the fact that in these constructions the tumblers are carried 15 on the rear cover plate of the lock which is torn away when the spindle is driven inwardly.

The principal object of this invention is to provide means for preventing the lock from 20 being unlocked after the spindle, tumblers and back plate have been forced out of place, thus frustrating unlawful attempts to enter the protected structure by displacing these 25 parts of the lock. A further object of this invention is to provide a protection device of the character referred to which does not interfere in the least with the normal operation of the lock, and effects no change in the usual 30 manner of manipulation. A further object of this invention is to provide a protection device of the character described which is efficient, yet simple and inexpensive in construction, and one which is adapted to be associated 35 readily and easily with locks of different standard constructions. Other objects of this 40 invention will be in part obvious and in part pointed out hereinafter.

In accordance with this invention, the protection device comprises means, for instance, 45 a catch or lug, which is adapted automatically to engage and hold the bolt bar in locked position as soon as and as long as a certain part of the lock, for instance, the rear cover plate, is displaced from its normal position, said means, however, being continually maintained in position out of engagement with the bolt bar so long as the controlling lock part is in proper position.

In order that a clearer understanding of 50 this invention may be had, attention is hereby directed to the accompanying drawings, forming a part of this application, and illustrating one possible embodiment of the invention.

Referring to the drawings, Fig. 1 is a sectional view, partly in elevation, of a mounted combination lock assembly, embodying this invention; Fig. 2 is a rear view of the lock; Fig. 3 is an interior view thereof, taken beneath the rear cover plate, and on the line 3—3 of Fig. 1; Fig. 4 is a sectional view of the lock case and bolt bar with the rear cover plate displaced, and is taken on the line 4—4 of Fig. 3; and Fig. 5 is a view similar to Fig. 4 but shows the rear cover plate in place. 55 Similar reference characters refer to similar parts throughout the several views of the drawings.

Referring to the drawings, the lock, in the main, is of standard construction, comprising 60 a case 1, rear cover plate 2, provided with an arbor 3 on which the combination tumblers 4 are mounted, and a drive tumbler 5 mounted on the operating spindle 6 which projects through the wall (double) 7 of the 65 protected structure, and which carries the usual dial 8 and operating knob 9. The lock case is secured to the wall 7 by means of screws 10. Mounted within the case are the slidable bolt bar 11 and the bolt bar operating dog 12. 70

As illustrating one possible embodiment of 75 this invention, there is shown a flat spring 14 seated in a depression 15 in the front 16 of the lock case, and is secured thereto at one end by means of a screw or rivet 17. The 80 other end of the spring is bent as at 18, and extends through a perforation 19 in the case to engage in a notch 20 in the bolt bar 12 when the spring is allowed to assume its own position. This spring, however, is normally held with its end 18 out of the notch in 85 bolt bar by means of a plunger 21 which is slidably seated in a guide recess 22 in the lock case. At one end plunger 21 engages the spring, and at its other end is engaged by a 90 pin 23 carried on the rear cover plate of the lock. The guideway 22 may conveniently be formed in one of the bosses 23 which are engaged by the screws 24 which secure the rear cover plate on the case. 95

100 So long as the cover plate 2 is in place the spring catch 18 is maintained out of engagement with the bolt bar, and the lock may be operated in the normal and usual manner. This is due to the plunger 21 being held depressed by its engagement with cover pin 23, as long as the cover is in place. As soon as the cover plate with its pin 23 is displaced

from the case, spring 14 moves inwardly of the lock case and its angular end 18 moves into the notch 20 of the bolt bar and prevents the bolt bar from being retracted into unlocked position, even when the combination tumblers and the cover plate have been removed from the case. Thus it is apparent that unlawful entry into the protected structure cannot be gained by ripping away rear cover plate 2 or the combination tumblers, as by removing the combination dial and knob and pounding inwardly on the spindle. No instrument can be inserted through the spindle passage to release the catch 18 from the bolt bar. It is also apparent that locks of many standard constructions may be equipped readily and easily with the protection device described above.

If desired, instead of providing the pin 23 on the cover plate the plunger 21 may be lengthened so as to be engaged and depressed by direct contact with the cover plate 2. It is expected that other possible modifications within the scope of this invention will be apparent to those skilled in the art. Accordingly, as many changes could be made in the above construction and as many apparently widely different embodiments of this invention could be made without departing from the scope thereof, it is understood that all matter contained in the above description or shown in the accompanying drawings be interpreted as illustrative and not in a limiting sense.

What we claim is:—

1. The combination with a lock including a bolt bar having a notch, of means, including a plate spring self-engageable in the notch of the bolt bar, for preventing unlocking movement of the bolt bar, and means, including a lock element, for maintaining said plate spring disengaged from the notch of said bolt bar only while said element is in its proper place in the lock assembly.

2. In a lock of the character described, in combination, a case, a cover plate therefor, a bolt bar within the case, said bolt bar having a notch therein, a plate spring secured to the case and having an end self-engageable in the notch of the bolt bar, a plunger in the case extending from the spring to adjacent the cover plate, and means, including the cover plate, for depressing the plunger to hold the spring out of engagement

with the notch of said bolt bar only while the cover plate is in proper position on the lock case.

3. In a lock of the character described, in combination, a case having a depression in the outer surface thereof, a bolt bar within said case, said bolt bar having a notch therein, means self-engageable with said notch in said bolt bar mounted within said depression and extending through the case, for locking the bolt bar against movement, and means, including a lock element which maintains said first means out of engagement with said notch when said lock element is in normal position.

4. In a lock of the character described, in combination, a case having a depression in the outer surface thereof, said outer face being adjacent to the wall of the protected structure forming therewith a chamber, a bolt bar within said case, said bolt bar having a notch therein, means mounted within said depression, extending through an aperture in the case and self-engageable with said notch in said bolt bar, for locking the bolt bar against movement, and means, including a lock element which maintains said first means out of engagement with said notch when said lock element is in normal position.

5. In a lock of the character described, in combination, a case, a cover plate therefor, a bolt bar within the case, a spring plate on the case self-engageable with the bolt bar for preventing unlocking movement thereof, said case having a guide recess, and a plunger buried therein and adapted to hold said spring plate out of engagement with the bolt bar as long as the cover plate is in normal position on the case.

6. In a lock of the character described, in combination, a case, a cover plate therefor, a bolt bar within the case, a spring catch device secured to said case exteriorly thereof, said catch device having a portion projecting into said case and engageable with said bolt bar for preventing unlocking movement thereof, and means associated with said cover plate for normally holding said spring catch out of engagement with said bolt bar.

This specification signed this 6th day of January, 1927.

EDGAR M. BENHAM.
WILLIAM T. BENHAM.
